UNITED STATES PATENT OFFICE

LOUIS T. FREDERICK, OF VALPARAISO, INDIANA, ASSIGNOR, BY MESNE ASSIGNMENTS, TO CONTINENTAL DIAMOND FIBRE COMPANY, OF NEWARK, DELAWARE, A CORPORATION OF DELAWARE

TUBE MAKING MACHINE

Application filed March 11, 1927. Serial No. 174,687.

My invention relates to tube making machines, for example machines for winding sheets of material around a mandrel for producing tubes for insulating and other purposes. The general object of the invention is to provide a machine by which the output of an operator may be increased, the physical labor involved decreased both in amount and in tensity, and the pressure on the work increased to almost any desired extent with practically no increase in the amount of force which must be exerted by the operator. Details of construction by which these general characteristics are obtained will be hereinafter described.

In the accompanying drawings which show an embodiment of the invention.

Figure 1 is a side elevation of the complete machine in the act of winding a mica sheet upon the mandrel to produce a tube.

Figure 2 is a sectional end elevation on the line 2—2 Figure 1.

Figure 3 is a side elevation of the head portion of the machine showing the toggle arms in a different position from the one shown in Figure 1.

Figure 4 is similar to Figure 3 but shows the parts in still a different position.

Like numerals denote like parts throughout the several views.

In the illustrated form there is a work table 10 supported upon legs 12 of any suitable construction. At the head of the table there is a stationary guide roller 14. At the foot there is another, 16, which in practice remains in fixed position but for purposes of adjustment its axle 18 is supported in bars 20 extending horizontally backward and having oblique notches 22 spaced at intervals for receiving the axle.

An endless belt 24 of heavy canvas or other suitable material passes around the rollers 14, 16 and is supported in part upon the table top as illustrated in Figure 1.

Near the bottom of the main frame there is a subframe having side arms 26 having stationary pivots 28 near the lower end of the back legs 12. Between their ends these arms support an axle 30 carrying a guide roller 32. This is in reality a tensioning roller for it

over-rides the belt as illustrated and is manipulated by the operator in charging the machine, as will appear. Its positioning is controlled by a treadle 34 secured to the forward end of the arms 26 in convenient position to be reached by the foot of the operator.

Near the head end of the table, one on either side, are two standards 36. By preference they have vertical slots 38 for accommodating clamp screws 40 by which they may be vertically adjusted. According to the illustrated design the standards are arched to project over the body of the table and support stationary pivots 42 from which are suspended arms 44 which, as will hereinafter appear, possess certain characteristics of a toggle. At the free end these arms carry a roller 46 which engages belt 24 and for identification may be referred to as the "squeezing" roller. Another roller 48, which may be termed the "reacting" roller is arranged parallel to roller 46 and is supported by said arms at a point nearer the fulcrum 42.

A mandrel 50 is used with the machine and is provided with a crank 52 by which it may be rotated as well as moved bodily. The mandrel is not attached to the table but comprises a cylindrical roller which is supported upon the table above the belt.

In practice the operator first releases the treadle 34 so that the belt will be comparatively loose. He then lays a sheet of the material 54 upon the belt a slight distance behind the reacting roller 48, after first having applied shellac or other binder to the material in any usual or preferred manner. At this time the toggle arms 44 hang freely suspended as shown in Figure 3, the belt passing over the reacting roller 48, and the squeezing roller 46 being free to swing. The operator then, after wrapping the forward edge of the sheet of mica plate once around the mandrel to start the winding of the tube in the ordinary manner, presses the mandrel down onto the table top and at the same time moves it forward toward the head end of the table as illustrated in Figure 4. This forms a bight in the belt as shown, the roller 46 yielding as the mandrel advances and finally dropping down behind it after the mandrel has

passed. The operator then presses upon treadle 34 which tightens the belt and pulls the mandrel backward again toward the rear of the machine, thus forcing the toggle arms 44 to straighten downward and move the squeezing roller 46 down toward the table top as shown in Figure 1. This straightening of the arms is analogous to a toggle action, and the pressure will of course increase in proportion as the squeezing roller approaches the table. As the reacting roller 48 is in the present form also mounted on the toggle arms, it also moves backward slightly as the squeezing roller moves backward, thus still further increasing the tightening action. When the desired tension has been attained the operator rotates crank 52 which winds up the work sheet 54 upon the mandrel, thus producing a tube. When the work sheet is entirely wound the operator releases the treadle 34 and reverses the program of manipulation of the mandrel, thus freeing it from the machine.

From the above description it will be evident that the operator's labor is greatly reduced and his output also increased. It is possible for him to gain a very high intensity of pressure without much effort on account of the toggle effect of the head frame or toggle arms 44. After the mandrel is locked in place, as shown in Figure 1, it is automatically prevented from displacement and all the operator has to do is to rotate the crank. There is no danger that the mandrel can become slightly oblique, which would thus produce a spiral wrapping of the work sheet and an imperfect tube. For these reasons the labor and watchfulness required of the operator are greatly reduced, and his output correspondingly increased.

I do not herein claim the novel method of making tubes, since the same forms the subject matter of a co-pending application, Serial Number 462,556, filed June 20, 1930.

Having thus described my invention, what I claim as new and desire to secure by Letters Patent is:—

1. A tube making machine having a table, a belt supported on the surface of the table and carrying the work, a mandrel arrangeable within a bight in said belt, guide rollers for the belt, and a pair of pivoted toggle arms for supporting one of the rollers to swing above the table from an altitude greater than the diameter of the mandrel to another position less than the diameter of the mandrel whereby to squeeze the mandrel within the bight in proportion as the last mentioned roller approaches the table.

2. A tube making machine having a table, an endless belt supported in part by the table, guide rollers for the belt, and toggle arms having stationary pivots, a guide roller mounted to the free ends of the arms, and another of the guide rollers being located parallel to the table top near the pivot of said

arms, said belt being folded about said rollers and forming a bight adjacent to the toggle arms, and a mandrel enfolded in said bight.

3. A tube making machine having a belt, a table across which the belt travels, a plurality of guide rollers supported adjacent said table and around which the belt is carried, a squeezing roller mounted above the table in position such that the belt may be arranged to form a bight between the squeezing roller and the table, and a mandrel arranged within the bight, said squeezing roller being movable bodily to and from the table and means for tensioning the belt, whereby to squeeze the mandrel within the bight.

4. A machine of the class described, having a reacting roller, a plurality of guide rollers, an endless belt passing around said guide rollers, and a mandrel arrangeable within a bight of the belt, said reacting roller movably engaging said belt adjacent said bight, to tension the belt about the mandrel, one of the guide rollers being manually controlled for tightening and loosening the belt.

5. A tube making machine having an endless belt, a support for said belt comprising a stationary member and a plurality of guide rollers around which the belt passes, a mandrel, arrangeable in a bight of the belt adjacent said stationary member and a squeezing roller adapted to contact the opposite side of the belt from the side contacted by the mandrel, said squeezing roller being arranged parallel to the stationary member and movable relatively to it having an axis parallel to the stationary member to engage and squeeze the belt about the mandrel when the squeezing roller is moved toward the stationary member, one of the guide rollers being manually controlled for tightening and loosening the belt.

6. A tube making machine having an endless belt, a support for said belt comprising a stationary member and a plurality of guide rollers around which the belt passes, a mandrel, arrangeable in a bight of the belt adjacent said stationary member, a squeezing roller adapted to contact the opposite side of the belt from the side contacted by the mandrel, said squeezing roller being arranged parallel to the stationary member and supported on pivoted toggle arms to swing toward and from the table to vary the pressure of the belt upon the mandrel, one of the guide rollers being manually controlled for tightening and loosening the belt.

7. A tube making machine having a table, an endless belt passing along the surface of the table for supporting the work a mandrel enfoldable within the belt, guide rollers for the belt, a pair of toggle arms for supporting one of the rollers, said arms having pivots fixed relatively to the table and so located that the last mentioned roller may be swung from a position farther from the table top than the

- diameter of the mandrel to another position closer to the table top than the diameter of the mandrel to engage the belt adjacent the mandrel and cause the belt to contract upon the mandrel in proportion as the last mentioned roller approaches the table top, and an additional guide roller manually movable parallel to its axis for still further controlling the tension on the belt.
- 10 8. A tube making machine having a table, an endless belt passing along the surface of the table for supporting the work, a mandrel enfoldable within the belt, guide rollers for the belt, a pair of toggle arms for supporting one of the rollers, said arms having pivots fixed relatively to the table and so located that the last mentioned roller may be swung from a position farther from the table top than the diameter of the mandrel
- 15 20 to another position closer to the table top than the diameter of the mandrel to engage the belt adjacent the mandrel and cause the belt to contract upon the mandrel in proportion as the last mentioned roller approaches the table top, one of the guide rollers being mounted on said arms near their supporting pivots, and an additional guide roller manually movable parallel to its axis for still further controlling the tension on the belt.
- 25 30 9. A tube making machine having a table, a mandrel, an endless belt supported in part by the table and adapted to enfold the mandrel, guide rollers for the belt, and toggle arms having stationary pivots, one of the guide rollers being mounted at the free end of the toggle arms parallel to the table top, and another of the guide rollers being located parallel to the table top near the pivot of said arms, another of the guide rollers being mounted in a movable sub-frame manually controllable whereby the belt may be loosened while the mandrel is being enfolded.
- 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935
- by said rollers and supported partially on said table and a mandrel arrangeable within a bight of the belt, a toggle arm carrying a roller in position to engage said belt adjacent said bight and means for tensioning the belt.
13. In a machine of the class described having a table, a plurality of guide rollers supported adjacent the table, a belt carried by said rollers and supported partially on said table and a mandrel arrangeable within a bight in the belt, reacting means pivoted to swing above said table, being arranged to swing away from the table to allow the mandrel to pass beneath in one direction into the bight and a stop preventing said reacting means from swinging away from the table in the opposite direction and means for tensioning the belt.
14. In a machine of the class described the combination of a table, a belt supported on said table, reacting means pivoted to swing in a limited path above said table, said belt passing around said reacting means and forming a bight between said reacting means and said table, a mandrel arrangeable in said bight, being movable along said table above said belt and beneath said reacting means, said reacting means being arranged to swing partly to allow the mandrel to pass into the bight, and means for tensioning the belt.
15. A tube making machine having a table, a belt supported in part by the table, shiftable reactive means mounted above said table and shiftable away from the table, said belt being arranged around said reactive means to form a bight between the table and said means, a mandrel arrangeable within said bight, and means for tensioning said belt to draw the same tightly around said mandrel to force same against said reactive means.
- In witness whereof, I have hereunto subscribed my name.
- LOUIS T. FREDERICK.
